TOOL

John W. Slayton, Jr., Pittsburgh, Pa.

Application August 24, 1946, Serial No. 692,836

2 Claims. (Cl. 306—35)

1

This invention relates to tools of the class having a working head and a handle for manipulating the head such as hammers, axes, hatchets, etc. In this application I have illustrated my invention as applying to a hammer, however it is equally applicable to other tools of this class.

Heretofore many expedients have been attempted to secure a head of a hammer to a handle. In one of the most frequently used methods the eye of a hammer head is tapered slightly towards the inner face of the head and a handle having an end tapered oppositely to the taper of the eye is inserted in the eye of the head. The end of the handle is then expanded by a wedge or screw. This method has never been entirely satisfactory. The head becomes loose as the wood shrinks during use and it is necessary to insert a larger wedge or screw which frequently splits the handle. Likewise there is a tendency for the wedge or screw to fall out. It has also been proposed to impregnate the wood so as to embrittle it and thus prevent shrinkage of the wood during use. However, if a wedge is driven into the end of a handle which has been so treated the brittle portion of the handle splits and this split is carried along a substantial length of the handle. My invention provides means for fastening a head to a handle in a secure manner and avoids the foregoing difficulties among others. At the same time the head and handle may be readily disengaged whenever desired.

In the drawings accompanying this specification I have illustrated a present preferred embodiment of my invention in which:

Figure 1 is a plan view of a hammer with certain portions removed for purposes of illustration; and

Figure 2 is a front elevation view with certain portions thereof in section; and

Figure 2A is an isometric view of a cap which may be secured to a hammer head; and

Figure 3 is a plan view of the inner face of a hammer head with the handle shown in cross section; and

Figure 4 is a front elevation view with portions thereof in section of a modification of my invention.

A tool constructed in accordance with my invention comprises a hammer head 5 of conventional design having an eye 6 which is inwardly tapered and extends to the point 6' as shown in Figures 2 and 4 of the drawings. A handle 7 is inserted into the eye 6 and secured there by means hereinafter described.

The outer end 8 of the handle 7 is outwardly

flared as shown in Figures 2 and 4 to cooperate with the inwardly extending taper of the eye 6. The lateral dimensions of the end 8 are so proportioned with respect to the smallest corresponding lateral dimensions of the eye 6 that the handle 7 may be inserted into the eye through the lower face of the head 5. Thus the largest lateral dimensions of the end 8 may be slightly smaller than the smallest corresponding dimensions of the eye 6 or a notch 8' may be cut in the end 8 as shown in Figure 2. By using the notch the end 8 may be "maneuvered" into the eye through the lower face of the head so long as the distance from the deepest point of the notch to the corner formed by the side opposite the notch and the top of the handle is less than the distance across the inner end of the eye. The width of the portion of the handle immediately below the notch should also be less than the distance across the inner end of the eye.

After the handle is inserted in the eye, filler members 9 and 10 are inserted into the eye 6 and around the handle end 8 to hold the end tightly in the eye. As shown particularly in Figures 1 and 3 of the drawings the filler members 9 and 10 are U-shaped in section and are of sufficient size to extend substantially around the periphery of the end 8 and thus form a sleeve which holds the handle in the eye.

The outer face of the head 5 is recessed to hold a rectangular plate or cap 11 which extends across the outer end of the handle and is secured to the head 5 by screws 12 which pass through the ends of the plate. The cap is preferably made of resilient metal and as shown in Figure 2A is curved before being attached to the head. When the screws 12 are tightened, the cap exerts an inward pressure on the handle end 8 and holds it against the sleeve members 9 and 10. If the handle end 8 shrinks in cross section the cap will force it further inward and thus a secure connection between the head and the handle will be maintained.

Various means may be employed to prevent the sleeve formed by the filler members 9 and 10 from sliding inwardly along the handle 7. In Figure 2 portions of the inner face of the head 5 which extend beyond the eye 6 are bent over at the point 6' to form flanges 13 and 14 which extend transversely across the head below the eye and press against the inner ends of the filler members 9 and 10. In Figure 3 an alternative method for holding the sleeve formed by the filler members is shown. The corners formed by the inner face of the hammer below the eye 6 are swedged

over to form triangular-shaped flanges 15 which press against the inner ends of the filler members 9 and 10. In another modification, the outer ends of the filler members may be bent over to form laterally extending flanges 16 and 17 as shown in Figure 4 of the drawings. The head 5 is recessed to seat these flanges beneath the plate or cap 11 and the plate and flanges are held in place by the screws 12.

The head and handle are assembled as follows: first, the outwardly flared end 8 of the handle 7 is inserted into and through the eye 6 of the head 5 through the inner face of the head. Thereafter the filler members 9 and 10 are placed in the eye around the end 8 of the handle. The handle is then pulled back and wedged in the eye in its correct position. The dimensions of the eye 6, the end 8, and the filler members 9 and 10 are such that a very tight fit results. Thereafter the plate 11 is seated in the recess of the head 5 and secured thereto by the screws 12.

It will be seen that a tool constructed in accordance with my invention avoids the need for wedges, screws, or the like to expand a handle within the eye of the tool head to secure the head to the handle. The filler members provide a sleeve which substantially surrounds the end portion of the handle within the eye and which due to the outwardly flared shape of the handle end prevents the head from flying off the handle. The plate 11 prevents the head from sliding inwardly along the handle. Since no wedges are driven into the end of the handle, the handle may be impregnated or otherwise treated to improve the quality and permanence of the material from which the handle is formed. Shrinkage of the handle end is thereby reduced. While a secure fastening of the head to the handle is thus obtained, nevertheless the head may be readily removed from the handle should it ever be necessary to do so.

While I have described a present preferred em-

bodiment of my invention it is to be understood that it may be otherwise embodied within the scope of the following claims.

I claim:

1. A tool of the class described comprising a head having an eye, a handle having an end fitting within the eye, the end having at least one outwardly sloping face, a notch in a face of the handle end to facilitate inserting the handle in the eye, the distance from the innermost point of the notch to the point on the face of the end opposite from the notch which is farthest from the notch being less than the smallest distance across the eye, the width of the handle immediately below the notch also being less than the smallest distance across the eye, and means for restraining longitudinal movement of the filler member.

2. A tool of the class described comprising a head having an outwardly tapering eye, a handle having an end to fit within the eye, at least one face of the handle end sloping outwardly, a filler member between the handle end and the eye for preventing retraction of the handle and a bowed resilient plate secured to the head and pressing upon the end of the handle to prevent protrusion thereof beyond the eye.
